UNITED STATES PATENT OFFICE.

NICHOLAS LAUER, OF DANSVILLE, NEW YORK.

IMPROVEMENT IN MEDICAL COMPOUNDS OR SALVES.

Specification forming part of Letters Patent No. 124,751, dated March 19, 1872.

To all whom it may concern:

Be it known that I, NICHOLAS LAUER, of Dansville, in the county of Livingston and State of New York, have invented a new Medical Compound or Salve; and I do hereby declare that the following is a full, clear, and exact description thereof:

The nature of my invention consists in mixing together oxide of zinc, one drachm; sal ammoniac, four drachms; subacetate of copper, one drachm; mutton-tallow, one thousand drachms; oil bergamot, one drachm; and olive-oil, one thousand drachms. This forms a salve, and is useful for the cure of skin diseases and also for the removal of dandruff.

The oxide of zinc acts as a mild tonic, desiccant, and absorbent. The sal ammoniac is a stimulant and resolvent, and possesses cooling, cleansing, and healing properties. The

subacetate of copper is a detergent, escharotic, external stimulant, and removes surface deposits. The olive-oil relaxes the skin and serves as a vehicle or diluent. Mutton-tallow softens and heals, and the bergamot perfumes.

I have found the above-named proportions to give the best results, but I do not confine myself to the exact proportions given. Neither do I confine myself to the bergamot-oil, as this may be omitted or some other perfume substituted in its stead.

I claim as my invention—

A medical salve, composed of the ingredients herein named, mixed together in about the proportions set forth.

NICHOLAS LAUER.
